(57) **CLAIM**

We claim the ornamental design for a lighting fixture long visor, as shown and described.

DESCRIPTION

FIG. 1 is a front, left side perspective view of the lighting fixture long visor;

FIG. 2 is a top view thereof;

FIG. 3 is a rear, right side perspective view thereof;

FIG. 4 is a left side elevation view thereof;

FIG. 5 is a right side elevation view thereof;

FIG. 6 is a front elevation view thereof; and,

FIG. 7 is a bottom view thereof.

The broken line showing is included for the purpose of illustration only and forms no part of the claimed design.
